COMBINATION PULVERIZING AND
CLASSIFYING MACHINE

Norwood H. Andrews, Moorestown, N. J., assignor,
by mesne assignments, to Freeport Sulphur
Company, New York, N. Y., a corporation of
Delaware

Application August 3, 1949, Serial No. 108,266

8 Claims. (Cl. 241—39)

1

This invention relates in general to a device for classifying a product of pulverization and more particularly to a type thereof in which a partially comminuted material may be further reduced in size while being classified and selectively carried off to a collector system.

The combination pulverizing and classifying machine to which this invention relates, herein-after referred to as the classifier, is an improvement upon the device disclosed in the Andrews and Willoughby Patent No. 1,953,058. The separator portion of said device has been found in practice to operate unsatisfactorily under certain conditions. For example, since it is usually desirable to collect only uniformly small particles, called fines, the gas within the separator must circulate at a very high speed in order to provide a centrifuge of sufficient strength to prevent the large particles from being entrained with said small particles or fines as they leave said separator. However, said high speed rotation of said gas not only causes the large, or oversize, particles to be centrifuged out of the rotation gas against the cylindrical wall of the separator but also causes a substantial quantity of the fines to do likewise. As the large particles are pulled down said wall by gravity, said centrifuged fines, which would otherwise be carried off to the collector, may also be carried downwardly with said large particles. This mixture of large and small particles drops into the bed of partially comminuted material and the bottom of the separator.

This situation becomes more clear when it is remembered that after the usual grinding operation, particularly of the impact type, the particles of shattered material are not all uniformly large and uniformly small, but rather are of a wide gradation of sizes. In present equipment, the separation of extreme heavies and extreme fines is accomplished satisfactorily, but there are large quantities of materials of borderline sizes which cause trouble. Usually, to insure against oversize particles getting into the product, it is necessary to run the classifier in such a manner that many suitable fines are actually returned to the grinding zones with the heavies returned for regrinding. Thus, an undesirable recirculation of satisfactorily ground fines becomes necessary.

Furthermore, said centrifuged fines, instead of distributing themselves uniformly upon said bed as they return thereto, may tend to load up near certain nozzles and, due to their poor flowability, reduce the effectiveness of these certain nozzles.

It has also been found that fines, as well as medium size particles, often tend to adhere to each

2

other in said separator because of the inherent cohesiveness of certain materials or, perhaps, because of a static electrical charge thereon effected by the rapid circulation of the particles. The resulting groups of small and medium size particles are drawn downwardly by gravity, along with the said large particles, into the said bed. Thus, additional energy must then be expended in separating such particles from each other.

Accordingly, a primary object of this invention is the provision of a combined pulverizing and classifying machine preserving the advantages of certain earlier machines, especially that disclosed in said Patent No. 1,953,058, while overcoming the disadvantages found in such machines, such as the difficulty encountered in handling medium size particles and agglomerates of small and medium size particles.

A further object of this invention is the provision of a pulverizing and classifying machine, as aforesaid, in which the uniformity of output may be increased without increasing the input energy requirements.

A further object of this invention is the provision of a pulverizing and classifying machine, as aforesaid, in which large particles are separated from a mass of partially comminuted material, pulverized to the required size and expelled from said machine into a suitable collector with a minimum expenditure of energy.

A further object of this invention is the provision of a pulverizing and classifying machine, as aforesaid, in which small particles about to be removed to a collector are prevented from improperly returning to the bed of the machine more effectively than has hitherto been possible.

A further object of this invention is the provision of a pulverizing and classifying machine, as aforesaid, in which small and/or medium particles, which have been raised through a substantial portion of the machine and have then formed an agglomerated mass of particles, due to mutual adherence, are separated from each other and discharged as fines before they can return to the bed of the machine.

Other objects and purposes of this invention will become apparent to persons familiar with this type of equipment upon referring to the accompanying drawings and upon reading the following specification.

In meeting those objects and purposes heretofore mentioned, as well as others incidental thereto and associated therewith, I have provided a combined pulverizing and classifying machine comprising a vertically disposed, cylindrical

grinding chamber, a similar, coaxial, outwardly and upwardly positioned circulation chamber and a vertically disposed, cylindrical, secondary classifying chamber coaxial with said circulation chamber and connected to the top thereof by means of an upwardly expanding, conical connection piece. The circulation chamber is provided with a circumferential slot covered by an external jacket or casing.

An upwardly expanding cone is supported within said circulation chamber adjacent to and spaced from a horizontally disposed, circular, primary classifying chamber at the upper end thereof. The lower end of the circulation chamber, which holds the partially comminuted material, such as the product of a mechanical grinder, is provided with a plurality of jets through the sidewalls thereof through which a fluid, such as steam, is ejected into said grinding chamber.

The secondary classifier has a coaxial opening in the top thereof and an upwardly expanding cone supported therewithin adjacent to said top and spaced therefrom.

The secondary classifying chamber, the circulation chamber and the primary classifying chamber are all operably connected to a vertical pipe adjacent thereto.

For illustrations of a particular, preferred embodiment of the invention, attention is directed to the accompanying drawings in which:

Figure 1 is a broken, side elevation view of the combined pulverizing and classifying machine to which this invention relates.

Figure 2 is a sectional view taken along the line II—II of Figure 1.

Figure 3 is a sectional view taken along the line III—III of Figure 1.

Figure 4 is a sectional view of Figure 1 about as taken along the line IV—IV of Figure 3.

Construction

The combination pulverizing and classifying machine 10, hereinafter referred to as the classifier (Figure 1) inasmuch as this invention is only in the classifying portions thereof, is comprised of a circulation housing 11 and a secondary classifying housing 12 preferably positioned directly above said circulation housing 11.

The circulation housing 11 has a cylindrical, axially vertical sidewall 13 supported upon and secured to a circular base plate 14. The upper edge of said wall 13 is partially covered by and secured to a flat rim 15 (Figures 1, 3 and 4) having a circular, inner opening 16 of less diameter than the inside diameter of the cylindrical sidewall 13. The base plate 14, sidewall 13 and rim 15 define the grinding chamber 17. A cylindrical, axially vertical discharge tube 18 (Figure 1), which may be similar to the discharge tube described and disclosed in the aforementioned Patent No. 1,935,058, is positioned within the lower portion of the grinding chamber 17, coaxial therewith and supported upon the base plate 14.

The sidewall 13 is provided with a circumferential slot (or plurality of small, aligned openings 21) (Figure 4) which preferably extends substantially completely around the cylindrical sidewall 13 and preferably lies in a plane substantially perpendicular to the axis of the said wall 13. An exterior casing or jacket 22 (Figures 1 and 4) encircles the cylindrical sidewall 13 enclosing the circumferential slot 21 and providing a circular by-pass chamber 19 between said jacket 22 and said wall 13. The jacket 22 is preferably, but not necessarily, comprised of an upper, down-

wardly expanding, conical rim 23 and a lower, upwardly expanding, conical rim 24, said rims being secured to each other, as by welding, along those adjacent edges of each which are of expanded diameter. The opposite edges of said rims, which are of less diameter, are secured, as by welding, to the outside of the cylindrical sidewall 13. The said jacket 22 is preferably so positioned that the circumferential slot 21 communicates between the circulation chamber 17 and by-pass chamber 19 just above the circle of contact between the cylindrical sidewall and the lower edge of the lower rim 24.

For the purpose of convenience in description the terms "upper" or "upwardly" and "lower" or "downwardly" shall herein be understood to refer to the classifier when positioned and/or operating in its normal manner of use. The terms "inner" or "inwardly" and "outer" or "outwardly" shall be understood to have reference to the geometric center of the classifier 10, and parts thereof, as herein described.

A materials hopper 25 (Figure 1) for supplying partially comminuted materials to the lower end of said circulation chamber 17, is preferably connected by means of the hopper pipe 26 to the said chamber 17 at a point intermediate the slot 21 and the base plate 14. It will be clearly understood, however, that the material hopper 25 may be replaced by any other suitable means for supplying partially comminuted materials to the chamber 17 such, for example, as a mechanical grinding machine.

The lower end of the cylindrical sidewall 13 of the classifying housing 12 is provided with a plurality of jets 28 through which an appropriate pulverizing gas, such as steam, may be ejected. The jets 28 are preferably aligned with small inlet openings 20 in the discharge tube 18. The partially comminuted material 27 is discharged from the hopper 25 through the pipe 26 into the bottom of the chamber 17 around the discharge tube 18, all as set forth in detail in Patent No. 1,935,058. Of course, insofar as the classifier involved in this invention is concerned, any grinding means discharging a high velocity stream of particle laden gas may be substituted for the grinding means here specifically indicated.

A cylindrical sleeve 29 is positioned within the circular inner opening 16 of the flat rim 15 and secured to said flat rim by any suitable means, such as welding, so that it is substantially coaxial with the cylindrical sidewall 13. The lower portion of the sleeve 29 extends down into the circulating chamber 17 and the lower edge 30 thereof is preferably curved slightly inwardly. A circular upper plate 31 is secured to the upper edge of the sleeve 29, as by welding, said plate having a circular pipe opening 32 therethrough coaxial with said sleeve 29. A center pipe 33 extends through said pipe opening 32 coaxial with the cylindrical sleeve 29 and secured to the upper plate 31, as by welding or brazing. The lower edge of said center pipe 33 preferably extends below the lower edge 30 of the sleeve 29 and the upper edge of said center pipe 33 preferably extends above the upper plate 31 and is provided with an integral connection flange 34.

A downwardly expanding, conical sleeve 35 coaxial with the sleeve 29 is secured therewithin along its upper edge to the bottom of said upper plate 31. The lower edge of said conical sleeve 35 is spaced a short distance from the inside wall of the cylindrical sleeve 29 just above the inwardly curved edge 30 thereof. Thus, a circular

primary classifying chamber 36, having a substantially triangular cross-section, is provided and defined by the conical sleeve 35, the cylindrical sleeve 29 and that portion of the upper plate 31 between said cylindrical and conical sleeves 29 and 35, respectively. Access to the primary classifying chamber 36 may be gained through the annular slot 37 provided between the lower edge of the conical sleeve 35 and the adjacent wall of the cylindrical sleeve 29 just above the curved edge 30 thereof.

An upwardly expanding lower cone 38 (Figure 4) is coaxially supported within the upper portion of circulation chamber 17 upon the sidewall 13 thereof by any suitable means, such as the support brackets 39. The cone 38 is provided with a small apex opening 41 through the lower or apex end thereof. The upper, expanded edge 42 of the cone 38, which extends around and above the lower edge 30 of the cylindrical sleeve 29 and is spaced a slight distance therefrom, is also spaced slightly downwardly from the flat rim 15. Thus, a conically shaped annular passageway 43 is provided between the upper portion of the lower cone 38 and the inwardly curved portion 30 of the cylindrical sleeve 29. It will also be seen in Figure 4 that the lower end of the center pipe 33 extends down into the lower cone 38.

The classifying housing 12 (Figure 2), which is positioned directly above the circulation housing 11 (Figure 1), has a cylindrical sidewall 44 substantially coaxial with the circulation chamber 17 and surrounding cylindrical secondary classifying chamber 45. The classifying housing 12 is spaced upwardly from the circulation housing 11 by an upwardly expanding conical connection piece 46, whose upper edge is secured to the lower edge of said sidewall 44 as by brazing or welding. The lower end of the connection piece 46 is provided with a connection flange 47, substantially similar to the connection flange 34 on the upper end of the center pipe 33 and securable thereto by any suitable means, such as bolts 48.

The top edge of the cylindrical sidewall of the secondary classifying chamber 45 is engaged by and secured to a substantially horizontal, circular top plate 49, which plate is provided with a circular discharge opening 51 substantially coaxially with the cylindrical sidewall 44. A cylindrical discharge pipe 52, which is preferably substantially coaxial with the cylindrical sidewalls 44 extends through the discharge opening 51 and is secured to the top plate 49 by any suitable means, such as welding or brazing. The upper end of said discharge pipe 52 may be connected by any suitable means, such as a discharge duct 53 (Figure 1), to an appropriate collection system (not shown).

An upwardly expanding upper cone 54 is coaxially supported upon the sidewall 44 within the secondary classifying chamber 45 near the upper end thereof by means such as the support brackets 55. The upper edge of said upper cone 54 surrounds and extends above the lower end of the discharge pipe 52 and is spaced downwardly from the top plate 49, inwardly from the cylindrical sidewall 44, and outwardly from said discharge pipe 52. The upper cone 54 is provided with a small apex opening 56 in the lower end thereof.

An upwardly expanding, conically shaped baffle ring 57, is coaxially supported within the secondary classifying chamber 45 upon the cylind-

rical sidewalls 44 thereof by means of support brackets 58. The baffle ring 57 is preferably so positioned that the apex opening 56 lies between the planes defined by the upper and lower edges 59 and 61, respectively, of said baffle ring 57. The upper larger edge 59 of the baffle ring 57 is spaced from the inside surface of the cylindrical sidewall 44 a very short distance.

A circular inlet opening 62 is provided in the cylindrical sidewall 44 and the lower edge 61 of the baffle ring 57. The inlet opening 62 is preferably so positioned that its axis is substantially horizontal and tangential with the outermost radial portion of the said secondary classifying chamber 45. The upper end of a by-pass duct 63, whose vertical axis is preferably substantially parallel with the coincident axes of the grinding chamber 17 and secondary classifying chamber 45, communicates with the chamber 45 through the opening 62 in the sidewall 44 and is secured thereto as by welding. The lower end of the by-pass duct 63 communicates with the circular by-pass chamber 19 through a circular outlet opening 64 in the upper rim 23 of the jacket 22. The outlet opening 64 is preferably on substantially the same side of the classifier 10 as the inlet opening 62 in the cylindrical sidewall 44.

The by-pass duct 63 also communicates with the circular primary classifying chamber 36 by means of an intermediate pipe 65 which is operably connected thereto and extends through a circular outlet opening 66 in the cylindrical sleeve 29. The outlet opening 66 is preferably on the same side of the classifier 10 as the outlet opening 64 in the upper rim 23.

Accordingly, it will be seen that there are several paths of communication between the grinding chamber 17 and the secondary classifying chamber 35. One of such paths of communication is provided through the lower cone 38, the center pipe 33 and the connection piece 46. Entry to the lower cone 38 from the circulation chamber 17 may be accomplished either through the opening 41 in the lower end of the cone 38 or through the conical passageway 43 at the upper end of the said cone 38. Another path which may be taken by the partially comminuted material 27 is through the slot 21, by-pass chamber 19, the by-pass duct 63, and the inlet opening 62. Said material can also pass through the conical passageway 43, between the lower cone 38 and the cylindrical sleeve 29, through the lower cone 38, the slot 37, the primary classifying chamber 36, the intermediate pipe 65, the by-pass duct 63, and thence into the secondary classifying chamber 45.

It will be recognized that damper means 63a, 65a and 33a (Figures 2 and 4) of any convenient, conventional type may be provided within the by-pass duct 63, the intermediate pipe 65, and the center pipe 33, respectively, for the purpose of controlling the passage of said material 27 through the various above mentioned paths within the scope of this invention. Also, said duct 63, and pipes 65 and 33 may be fabricated of a particular diameter where the device is to be used for a particular constant performance. Further, the width of the circumferential slot 21, conical passageway 43, the slit 37, the space between the lower cone 38 and the flat rim 15 and the space between the upper cone 54 and the top plate 49 may be varied to meet the particular desired performance within the scope of this invention. If desired, the mounting of the cone 38 may readily be made adjustable by any of

7

several well known means, such as by providing slots 19 in the walls 13 of the circulation chamber 11, plates 11 on the cone supporting brackets 39 for covering said slots and passing bolts 13 through suitable, preferably non-circular, openings in said plates and thence through said slots.

Although, the description and disclosure herein are substantially directed to a classifier 10 fabricated from sheet metal or metal plate it will be clearly understood that any other type of structural material may be used to fabricate the classifier without departing from the substance and scope of this invention. It will be further understood that the exact contour of the outside of the device is of little importance as long as the conical and cylindrical inside contours are retained substantially as described and disclosed.

Operation

The partially comminuted material 21 flows from the materials hopper 25 into the bottom of the grinding chamber 17 around the discharge tube 18. A suitable grinding fluid, such as steam, is ejected through the jets 28 into the partially comminuted material 21 within at the bottom of the circulating chamber 17. Since the jets 28 are aligned with the inlet openings 20 in the discharge tube 18, the material 21 is carried through the openings 20, impacted and shattered, and swirled up the discharge tube 18 into the circulation chamber 17. This action is described in detail in the above mentioned Andrews and Willoughby patent.

The size of the slot 21, passageway 43, slit 37 and the diameter of the duct 63, the intermediate pipe 65 and the center pipe 33 are balanced as needed so that a strong flowing stream of the grinding fluid will pass through the slot 21 into the by-pass chamber 19 and the by-pass duct 63 into the secondary classifying chamber 45. This stream picks up and carries to said secondary classifying chamber any fines which may be sliding down the inside of the wall 13 and would otherwise return to the bed 27 of unground material. The remainder of the material 21 is carried up through the circulation chamber 17 and enters the lower cone 38 either through the opening 41 in the lower end thereof or through the annular passageway 43.

In view of the strong upward, axial, discharge of material laden gas from the discharge tube 18, there will be little or no swirling of said gas in the circulation chamber 17. However, the gas will circulate therein at high velocities and will, first, impose a substantial opposition to heavy particles, hereinafter described; dropping downward out of the cone 38 and carry some fine particles upwardly through the opening 41 and, second, carry the remainder of the substantially shattered particles to the top 42 of said cone 38 and into the passageway 43. The larger particles will drop out of the gas stream shortly beyond its high velocity zone immediately following discharge from the discharge tube 18.

The material laden gas now goes through the passageway 43 and divides. Part goes to the center and upward through the center pipe 33 and the remainder makes a sharp bend around the edge 30 and then goes upward through the passageway 37. Again heavies will drop out of the stream, partly by the slowing of the stream as it crosses the larger area between the passageway 43 and the center pipe 33 and partly by the heavies being unable to make the sudden turn around the edge 30. The amounts of gas taking

8

each of these paths is, of course, controlled by the sizes of the passageways 33 and 65, or by the settings of dampers therein. The heavies which drop out will go down through the cone 38, out the opening 41 and back to the bed 27 for regrinding. However, any agglomerates formed by this time will be broken up by the strong gas stream, and particles carried thereby, coming upward through the opening 41 and the particles resulting from such broken agglomerates will then rise back upwardly, or continue falling, according to their particular sizes.

The fines which are able to round the edge 30 of the cylindrical sleeve 29 then pass through the primary classifying chamber 36 and the pipe 65 into the duct 63, where they combine with the grinding fluid and fine particles which pass through the slot 21 and the by-pass chamber 19. This mass of fluid and particles then passes through the upper part of the by-pass 63 and into the secondary classifying chamber 45. Since the duct 63 enters said chamber 45 at a tangent to the radially outer portion thereof, the material entering the chamber through the duct 63 tends to swirl upwardly with a rotary motion through the chamber 45.

The oversize particles and agglomerations, which reach the chamber 45, are centrifuged toward the sidewall 44 of the chamber 45 where they are drawn downwardly by gravity along said sidewall, through the connection piece 46 and into the center pipe 33. Some fines may be entrained by said oversize and agglomerated particles and also move downwardly therewith. Substantially all of the fines which reach the center pipe 33 in this manner are entrained by the fines and grinding fluid passing upwardly through said center pipe and are thereby prevented from continuing downwardly through said center pipe. The downward movement of the oversize and agglomerated particles is also opposed by the aforementioned fines and grinding fluid passing upwardly through the center pipe 33 and some of the agglomerations are broken up with the particles thereof then moving back upwardly or continuing downwardly according to their individual sizes. Those oversize and agglomerate particles which drop through the center pipe 33 into the cone 38 are subjected to bombardment both by those medium and oversize particles entering said lower cone 38 through the passageway 43 which are unable to pass around the curved edge 30 and by the gas and material coming upwardly through the opening 41.

The individual functions of certain of the critical parts of the classifying device will now be examined in order that its principles may be more clearly disclosed. First, assume that the damper 63a is fully closed and the other damper is open so that the lower half of the conduit 63 becomes inoperative. Under these circumstances, no gas will flow out of the slot 21. This will not change any of the basic functions of the device, but such fines as may be agglomerated with, or entrained by, the heavies sliding down the inside wall of the circulation chamber 11 will be carried on down to the bed 27. With gas flowing out of said slot, however, most of such fines will be entrained thereby and carried up to the secondary classifier as above described. Therefore, the setting of the damper 63a, and/or the size of the slot 21, must be so balanced with respect to the conduits 33 and 65 that a strong current of gas will flow out through said slot.

Second, assuming that the damper in the center tube 33 is fully closed and the others are open, then there is nothing to effect agitation in the lower part of the secondary classifier, it acts as a mere cyclone and heavy material merely would gather at the bottom thereof.

Third, assuming that the damper in the pipe 65 is closed and the others are open, then all of the gas from the grinding operation, which gas, excepting for the relatively little that goes out through the slot 21, is needed to carry the material up and around the upper end of the cone 38, would necessarily go out through the center tube 33. This would create a stream therethrough of such high velocity that none of the heavies separated out by the secondary classifier would be permitted to fall back downwardly out of the secondary classifier. Therefore, enough of such gas is bled out through the pipe 65 to adjust the velocity of the stream through the center tube 33 to carry the fines upwardly but permit the heavies to fall downwardly through it.

The initial quantities and velocities of gas are, of course, determined by the requirements of convention impact grinding, which requirements are well known. The sizes and other capacity characteristics of the device are then designed to assure a high enough velocity of gas flow throughout all parts thereof to guard against the existence of dead pockets anywhere therein, and the conduits 63, 65 and 33 are all so designed, and/or their respective dampers adjusted, that there will be a strong flow through each, providing only that the flow through the center tube 33 is not too strong to permit the heavies to return downwardly through it.

Thus when the device is properly adjusted for a given set of operating conditions, the combined effects of the fines and grinding fluid surging upwardly through the center pipe 33, the bombardment by the medium and oversize particles in the lower cone 38, and the upward movement of fines and grinding fluid through the apex opening 41 tend to break up substantially all of the agglomerates before they can fall back into the said bed 27 of partially comminuted material. These effects also strongly inhibit any individual fines from falling back into said bed.

From this it will be seen that oversized particles made up from an agglomeration of fines and/or oversize will be broken up and their fine constituents will be prevented from passing down from the upper cone 54 to the bottom of the grinding chamber 17; first, by the upward movement of fines and grinding fluid through the apex opening 56; second, by the upward flow of fines and grinding fluid through the center pipe 33; third, by the impact of medium and oversized particles entering the lower cone 38 through the passageway 33; fourth, by the upward flow of fines and grinding fluid through the apex opening 41 in the lower cone 38; and fifth, by the exhausting of grinding fluid through the slot 21 in the sidewall of the grinding chamber 17.

By the time the partially comminuted material 27 reaches the discharge pipe 52 in the top of the secondary classifying chamber 45 it has been subjected to almost continuous classifying action, which action produces a uniformly fine product which is then exhausted through the discharge duct 53 to a suitable separating means, not shown.

While throughout the foregoing the opening 21 has been shown and described as an elongated

slot, it should be understood that it could as well be a series of closely spaced, aligned, holes.

Although the above mentioned drawings and description apply to one particular, preferred embodiment of the invention, it is not my intention, implied or otherwise, to eliminate other variations or modifications which do not depart from the scope of the invention unless specifically stated to the contrary in the hereinafter appended claims.

I claim:

1. In a classifying device receiving a stream of high velocity gas laden with particles of a plurality of sizes, the combination: a lower, substantially cylindrical, circulation chamber and means for dividing said chamber into an upper and a lower portion, said upper portion disposed axially of said lower portion and communicating with said lower portion near both the periphery and the center of each of said portions, a centrally located offtake extending upwardly from said upper portion; and a primary classifying chamber, annularly arranged surrounding said offtake and communicating near its periphery with said upper portion of said circulation chamber; a secondary classification chamber constituting a cyclone; means providing communication from said offtake to the bottom of said cyclone; means providing communication from said primary classification chamber to the side of said cyclone and discharging tangentially thereto; offtake means for said cyclone centrally positioned near the top thereof.

2. In a combined pulverizing and classifying device having upper and lower, vertically disposed, classifying chambers with cylindrical sidewalls, within which a material laden fluid may circulate, and connecting means between said chambers, the improved construction comprising in combination: a horizontal slot through the sidewall of said lower chamber and a jacket therearound, said slot extending around substantially the entire circumference of said side wall; fluid and material inlet means associated with the lower end of said lower chamber; an annular chamber horizontally disposed within the upper end of said lower chamber and having a slot through its bottom opening into said lower chamber; a by-pass duct providing intercommunication between said jacket, said annular chamber and said upper chamber said duct entering said upper chamber tangentially; and means effecting discharge of materials laden fluid from the upper end of said upper chamber.

3. In a combined pulverizing and classifying device having upper and lower, vertically disposed, coaxial cylindrical chambers with cylindrical sidewalls within which a material laden fluid may circulate, and connection means providing communication between said upper and lower chambers, the improved construction comprising in combination: a horizontal slot through the sidewall of said lower chamber and an external jacket therearound, said slot extending around a major portion of the circumference of said lower chamber; fluid and material inlet means at the lower end of said lower chamber; an annular chamber horizontally disposed within the upper end of said lower chamber, having an arcuate peripheral slot through the lower side thereof and having an outer wall spaced inwardly from the sidewall of said lower chamber; an axially vertical, upwardly expanding funnel within said lower chamber extending above and around the lower edge of the outer wall of said

annular chamber; a discharge pipe coaxial with said upper chamber and providing an outlet through the upper end thereof; and a by-pass duct providing intercommunication between said jacket, said annular chamber and said upper chamber.

4. In a combined pulverizing and classifying machine with upper and lower, vertically disposed, chambers having coaxial, cylindrical sidewalls within which a gas carrying partially comminuted material may circulate, and a coaxial connecting pipe between said chambers, the improved construction comprising in combination: gas and material inlet means associated with the lower end of said lower chamber; an annular chamber horizontally disposed within the upper end of said lower chamber, encircling the lower end of said connecting pipe and having an outer wall spaced radially inwardly from the sidewall of said lower chamber, said annular chamber having an arcuate peripheral slot through its lower side; an axially vertical, upwardly expanding funnel within said lower chamber, the upper edge thereof extending between and spaced from both the outer wall of said annular chamber and said lower chamber sidewall thereby effecting a double reversal in upward flow of said gas from said lower chamber to said annular chamber; means including a coaxial discharge pipe effecting discharge of material laden gas from said upper chamber into the area defined by said funnel; and a by-pass duct providing intercommunication between said annular chamber and said upper chamber.

5. In a combined pulverizing and classifying machine with upper and lower, vertically disposed, chambers having coaxial cylindrical sidewalls within which a gas carrying partially comminuted material may circulate, and a coaxial connecting pipe between said chambers, the improved construction comprising in combination: a horizontal slot through the sidewall of said lower chamber and a jacket around said sidewall covering said slot, said slot extending around the major portion of the circumference of said lower chamber; gas and material inlet means associated with the lower end of said lower chamber; an annular chamber horizontally disposed within the upper end of said lower chamber, encircling the lower end of said connecting pipe and having an outer wall spaced radially inwardly from the sidewall of said lower chamber, said annular chamber having an arcuate peripheral slot through its lower side; an axially vertical, upwardly expanding lower funnel within said lower chamber, the upper edge thereof extending between and spaced from both the outer wall of said annular chamber and said lower chamber sidewall thereby effecting a double reversal in the upward flow of said gas through said lower chamber; an axially vertical, upwardly expanding funnel within said upper chamber and spaced from the sidewall thereof, and discharge pipe extending upwardly and coaxially from within said upper funnel through the upper end of said upper chamber and thereby effecting a double reversal in the upward flow of said gas through said upper chamber; and a by-pass duct providing intercommunication between said jacket, said annular chamber and the lower end of said upper chamber.

6. In a combined pulverizing and classifying machine having upper and lower, vertically disposed, cylindrical chambers having coaxial cylindrical sidewalls within which a gas carrying par-

tially comminuted material may circulate, and an upwardly expanding, conical connection piece communicating between and coaxial with said upper and lower chambers, the improved construction comprising in combination: an external jacket surrounding the wall of said lower chamber and an elongated opening through said wall between said jacket and said lower chamber, said elongated opening extending around a major portion of the circumference of said lower chamber; gas inlet means, and means dispersing said material into gas emitted through said gas inlet means, associated with the lower end of said lower chamber; a horizontally disposed, annular chamber within the upper end of said lower chamber encircling the lower end of said connection piece and having an outer wall spaced radially inwardly from the sidewall of said lower chamber, said annular chamber having a peripheral slot through its lower side opening into said lower chamber; an axially vertical, upwardly expanding funnel within said lower chamber extending upwardly around and spaced outwardly from the outer wall of said annular chamber to form an annular passageway therebetween; means permitting passage of material laden gas from a point below said funnel to a point thereabove adjacent to said passageway; a by-pass duct providing intercommunication between said jacket, said annular chamber, and the lower end of said upper chamber; and means including a discharge pipe effecting discharge of materials laden gas from the upper end of said upper chamber.

7. In a combined pulverizing and classifying machine having upper and lower, vertically disposed, cylindrical, chambers having coaxial cylindrical sidewalls within which a gas carrying partially comminuted material may circulate, a tubular member extending upwardly out of said lower chamber and an upwardly expanding, conical, coaxial connection piece communicating with said upper chamber and the upper end of said tubular member, the improved construction comprising in combination: an external jacket surrounding the wall of said lower chamber and a narrow, elongated, horizontal slot through said sidewall between said lower chamber and said jacket, said slot extending around a major portion of the circumference of said lower chamber; a jet adapted for gas emission communicating with the lower end of said lower chamber and means for introducing said material into the path of said jet; a horizontal, annular chamber within the upper end of said lower chamber encircling the lower end of said connection piece, having a circular peripheral slot through its lower wall opening into said lower chamber, and having a radially outer wall spaced inwardly from the sidewall of said lower chamber; an axially vertical, upwardly expanding funnel within said lower chamber extending upwardly between and spaced from both an outer wall of said annular chamber and the sidewall of said lower chamber thereby forming a pair of concentric annular passageways therebetween; a discharge pipe coaxially extending from the upper end of said upper chamber; and a by-pass pipe providing communication between said jacket, said annular chamber and the lower end of said upper chamber, said by-pass pipe having a horizontal upper portion tangentially disposed to said upper chamber.

8. In a combined pulverizing and classifying machine for handling a gas carrying partially comminuted material, the combination comprising: a grinding chamber having a vertical cylin-

drical sidewall, horizontal bottom plate and top rim, and a circumferential slot through said sidewall; a plurality of jets adapted for gas emission communication with the lower end of said grinding chamber and means for introducing said material into the gas streams emitted from said jets; an external jacket surrounding said slot, said slot being adjacent to the lower edge of said jacket; an axially vertical sleeve secured within said rim, extending into said grinding chamber and spaced inwardly from the sidewall thereof; an upper plate covering the upper end of said sleeve and having a pipe opening coaxial therewith; a downwardly expanding, conical sleeve secured under said upper plate coaxially within said cylindrical sleeve, the lower edge of said conical sleeve being spaced from but adjacent to the lower edge of said cylindrical sleeve, thereby providing a horizontal, annular chamber communicating with said grinding chamber; an upwardly expanding funnel coaxially supported with said grinding chamber, the upper edge thereof extending upwardly between and spaced from both said sidewall and said cylindrical sleeve; a center pipe extending through said pipe opening down into said funnel; a vertical cylindrical classifier chamber coaxial

with said grinding chamber and having a discharge opening through the upper end thereof; a conical connection piece extending between the lower end of said classifier chamber and the upper end of said center pipe; a by-pass pipe providing communication between said jacket, said annular chamber, and the lower end of said classifier chamber, said by-pass pipe having a horizontal upper portion tangentially disposed to said classifier chamber.
